UNITED STATES PATENT OFFICE.

MONROE D. COLBATH, OF HAMPTON, MAINE

CARBURETER.

No. 820,554.

Specification of Letters Patent.

Patented May 15, 1906.

Application filed December 14, 1904. Serial No. 236,891.

To all whom it may concern:

Be it known that I, MONROE D. COLBATH, a citizen of the United States, residing at the city of Hampden, county of Penobscot, State of Maine, have invented certain new and useful Improvements in Carbureters, of which the following is a specification.

This invention relates to improvements in carburetors.

The objects of this invention are, first, to provide an improved carburetor in which the introduction of the air and the liquid hydrocarbon to the carburetor in proper proportions is automatically controlled; second, to provide an improved carburetor which is very simple and compact in structure and of large capacity and one which is not likely to get out of repair; third, to provide an improved carburetor in which the necessity of placing the carburetor in the cellar or providing a special housing therefor is avoided.

Further objects and objects relating to structural details will definitely appear from the detail description to follow.

I accomplish the objects of my invention by the devices and means described in the following specification.

The invention is clearly defined and pointed out in the claims.

A structure embodying the features of my invention is clearly illustrated in the accompanying drawings, forming a part of this specification, in which—

Figure 1 is a central vertical sectional view through a structure embodying the features of my invention, the piping and regulators being shown in full lines and the air-storage tank and the oil-pump being shown in conventional form. Fig. 2 is an enlarged longitudinal sectional view showing the structural details of the automatic oil-feed valve.

In the drawings similar letters of reference refer to similar parts in both views.

Referring to the drawings, I provide a storage tank or reservoir A for the liquid hydrocarbon. This storage-tank is preferably buried in the ground or arranged in a suitable vault. The storage-tank is provided with a suitable closure or cover a. The carburetor proper is arranged within this storage-tank, the cover a being of sufficient size to permit the ready insertion or removal of the same. The carburetor consists of the main carbureting-chamber B and an auxiliary carbureting-chamber B'. The auxiliary carbureting-chamber B' is connected to the main carbureting-chamber by a vertical tube C. Both the main and the auxiliary carbureting-chambers are provided with horizontally-arranged baffle-plates b, having perforations b' 60 therein. The perforations of the adjacent baffle-plates are arranged in a zigzag relation, so that the air and liquid hydrocarbon passing through the chambers are forced to take a zigzag course. If desired, a suitable wicking 65 or absorbant may be arranged between the baffle-plates. Within the tube C are hollow screens c, forming partitions across the same. Between these partitions is a suitable packing of absorbent material, as c'.

The air is introduced into the upper or auxiliary carbureting-chamber B' by the pipe D', which connects the same with the air-storage tank D. The air is supplied to this storage-tank from a suitable pump or motor, not 75 here illustrated. A suitable pressure-regulator D'' is provided for the air-supply pipe, so that the pressure of the air delivered is controlled.

The air-delivery pipe D' is arranged 80 through the oil-supply tank E, which is arranged on the oil-storage tank A above the carburetor. Arranged within the air-pipe D' and connected to the oil-delivery tank E by a passage e' is a valve-casing E'. This valve-casing is preferably centrally arranged in the air-pipe, so as to be surrounded by the air passing through the air-pipe. The valve e is arranged within the valve-casing E' and is provided with a stem e'', which projects 85 through the end of the casing. On the end of this stem is a disk valve f, adapted to close against the seat F in the air-supply pipe D'. (See Fig. 2.) The valves e and f open inwardly. A coiled spring e''' is arranged on 90 the stem e'' for retaining the valves normally in their seats. When the valve e is in its seat, the valve f is also seated, thereby cutting off the delivery of air and oil to the carburetor. The valve-casing E' is provided 95 with a plurality of perforations E'' in its under side for the delivery of the liquid hydrocarbon into the air-supply pipe.

A service-pipe G is connected to the main carbureting-chamber B near its bottom. 100 This service-pipe is provided with a pressure-regulator G', so that the carbureted air or gas is delivered at a predetermined pressure. The oil is supplied to the oil-supply chamber by the pump P, which is connected to the 105 storage-chamber at or near the bottom thereof. A pipe p' connects the pump to the sup-

ply-tank, the parts being here illustrated in conventional form. A check-valve *p*" is provided to prevent backflow.

The pressure-regulators *D*" and *G*' are set 5 at about the same point, so that when the pressure in the carbureter is relieved by drawing the gas or carbureted air from the service-pipe the air is admitted by the pressure-regulator *D*" of the supply-pipe. The 10 passage of air through the air-supply pipe forces the valve *f* from its seat, and thereby opens the oil-valve *e*, allowing the oil to flow past the same into the air-supply pipe, from which the air and oil pass together to the carbureter. As soon as the pressure in the carbureter again reaches a predetermined point the valves are returned to their seats by the coiled spring *e*'''', thus cutting off the supply 15 of both air and liquid hydrocarbon. The oil-20 valve *e* is so arranged that the amount of oil admitted therethrough is in proper proportion to the amount of air admitted by the valve *f*. In the passage of the air and oil through the carbureter they are suitably mixed. The 25 packing of absorbent material *c*' between the screens *c* absorbs the liquid hydrocarbon and holds the same in suspension, so that the air comes into thorough contact therewith.

If desired, a suitable packing of absorbent 30 material may be arranged between the baffle-plates *b* of the main and auxiliary carbureting-chambers.

With the parts thus arranged the amount 35 of oil admitted to the carbureter is properly proportioned to the amount of air admitted thereto, and this is governed by the amount of carbureted air or gas drawn from the service-pipe.

By arranging the carbureter within the 40 storage-tank the whole apparatus may be buried in the ground a desired distance from the building, so that it is unnecessary to store any oil in the building to which gas is supplied. The structure is also very compact 45 and of large capacity in proportion to its size.

I have illustrated and described my improved carbureter in the form preferred by me on account of its structural simplicity and compactness. I am aware, however, 50 that it is capable of considerable structural variation without departing from my invention.

Having thus described my invention, what I claim as new, and desire to secure by Letters Patent, is—

1. In a carbureter, the combination of an oil-storage tank or reservoir; an oil-supply tank supported above said storage-tank; a pump for delivering oil to said supply-tank; a 60 carbureter arranged within said oil-storage tank, connected to said oil-supply tank; consisting of a main carbureter-chamber and an auxiliary carbureter-chamber, connected by a vertical pipe or tube; perforated baffle-65 plates arranged in said chambers, the perfo-

rations of the adjacent plates being zigzagged; screens *c* forming partitions in said connecting-tube for said carbureter-chambers; a packing of absorbent material between said partitions; a service-pipe connected to said main carbureter-chamber toward the bottom thereof; an air-supply pipe arranged through said oil-supply tank; a valve-casing connected to said oil-supply tank, arranged in said air-supply pipe; an inwardly-opening oil-valve 70 having a suitable stem; an air-valve for the said supply-pipe, carried by said stem; a spring on the said stem for holding said valves normally in their seats; and pressure-regulators for said air-supply and service pipes, all coacting for the purpose specified.

2. In a carbureter, the combination of an oil-storage tank or reservoir; an oil-supply tank supported above said storage-tank; a pump for delivering oil to said supply-tank; a carbureter arranged within said oil-storage tank, connected to said oil-supply tank; a service-pipe connected to said carbureter; an air-supply pipe arranged through said oil-supply tank; a valve-casing connected to 85 said oil-supply tank, arranged in said air-supply pipe; an inwardly-opening oil-valve having a suitable stem; an air-valve for the said supply-pipe, carried by said stem; a spring on the said stem for holding said valves normally 90 in their seats; and pressure-regulators for said air-supply and service pipes, all coacting for the purpose specified.

3. In a carbureter, the combination of an oil-storage tank or reservoir; an oil-supply tank supported above said storage-tank; a pump for delivering oil to said supply-tank; a carbureter arranged within said oil-storage tank, connected to said oil-supply tank; consisting of a main carbureter-chamber and an auxiliary carbureter-chamber, connected by a vertical pipe or tube; perforated baffle-plates arranged in said chambers, the perforations of the adjacent plates being zigzagged; screens *c* forming partitions in said connecting-tube for said carbureter-chambers; a packing of absorbent material between said partitions; a service-pipe connected to said main carbureter-chamber toward the bottom thereof; an air-supply pipe; a valve-casing, 105 connected to said oil-supply tank; an inwardly-opening oil-valve having a suitable stem; an air-valve for the said supply-pipe, carried by said stem; a spring on the said stem for holding said valves normally 110 in their seats; and pressure-regulators for said air-supply and service pipes, all coacting for the purpose specified.

4. In a carbureter, the combination of an oil-storage tank or reservoir; an oil-supply tank supported above said storage-tank; a pump for delivering oil to said supply-tank; a carbureter arranged within said oil-storage tank; connected to said oil-supply tank; a service-pipe connected to the said carbureter; 125

- an air-supply pipe; a valve-casing connected to said oil-supply tank; an inwardly-opening oil-valve having a suitable stem; an air-valve for the said supply-pipe, carried by said stem; a spring on the said stem for holding said valves normally in their seats; and pressure-regulators for said air-supply and service pipes, all coacting for the purpose specified.
5. In a carbureter, the combination of an oil-supply tank; a carbureter connected thereto consisting of a main carbureter-chamber and an auxiliary carbureter-chamber, connected by a vertical pipe or tube; perforated baffle-plates arranged in said chambers, the perforations of the adjacent plates being zigzagged; screens *c* forming partitions in said connecting-tube for said carbureter-chambers; a packing of absorbent material between said partitions; a service-pipe connected to said main carbureter-chamber toward the bottom thereof; an air-supply pipe arranged through said oil-supply tank; a valve-casing connected to said oil-supply tank, arranged in said air-supply pipe; an inwardly-opening oil-valve having a suitable stem; an air-valve for the said supply-pipe, carried by said stem; a spring on the said stem for holding said valves normally in their seats; and pressure-regulators for said air-supply and service pipes, all coacting for the purpose specified.
6. In a carbureter, the combination of an oil-supply tank; a carbureter connected thereto; a service-pipe connected to said carbureter; an air-supply pipe arranged through said oil-supply tank; a valve-casing connected to said oil-supply tank, arranged in said air-supply pipe; an inwardly-opening oil-valve having a suitable stem; an air-valve for the said supply-pipe, carried by said stem; a spring on the said stem for holding said valves normally in their seats; and pressure-regulators for said air-supply and service pipes, all coacting for the purpose specified.
7. In a carbureter, the combination of an oil-supply tank; a carbureter connected thereto consisting of a main carbureter-chamber and an auxiliary carbureter-chamber, connected by a vertical pipe or tube; perforated baffle-plates arranged in said chambers, the perforations of the adjacent plates being zigzagged; screens *c* forming partitions in said connecting-tube for said carbureter-chambers; a packing of absorbent material between said partitions; a service-pipe connected to said main carbureting-chamber toward the bottom thereof; an air-supply pipe; a valve-casing connected to said oil-supply tank; an inwardly-opening oil-valve having a suitable stem; an air-valve for the said supply-pipe, carried by said stem; a spring on the said stem for holding said valves normally in their seats; and
5. In a carbureter, the combination of an oil-supply tank; a carbureter connected thereto; a service-pipe connected to said carbureter; an air-supply pipe; a valve-casing connected to said oil-supply tank; an inwardly-opening oil-valve having a suitable stem; an air-valve for the said supply-pipe, carried by said stem; a spring on the said stem for holding said valves normally in their seats; and pressure-regulators for said air-supply and service pipes, all coacting for the purpose specified.
8. In a carbureter, the combination of an oil-supply tank; a carbureter connected thereto; a service-pipe connected to said carbureter; an air-supply pipe; a valve-casing connected to said oil-supply tank; an inwardly-opening oil-valve having a suitable stem; an air-valve for the said supply-pipe, carried by said stem; a spring on the said stem for holding said valves normally in their seats; and pressure-regulators for said air-supply and service pipes, all coacting for the purpose specified.
9. In a carbureter, the combination of an oil-storage tank or reservoir; an oil-supply tank supported above said storage-tank; a pump for delivering oil to said supply-tank; a carbureter arranged within said oil-storage tank, connected to said oil-supply tank; consisting of a main carbureter-chamber and an auxiliary carbureter-chamber, connected by a vertical pipe or tube; perforated baffle-plates arranged in said chambers, the perforations of the adjacent baffle-plates being zigzagged; screens *c* forming partitions in said connecting-tube for said carbureter-chambers; a packing of absorbent material between said partitions; a service-pipe connected to the said main carbureter-chamber toward the bottom thereof; an air-supply pipe; a valve therefor; an oil-valve; connections for said air and oil valves, whereby said oil-valve is controlled by the opening and closing of said air-valve; and pressure-regulators for said air-supply and service pipes, all coacting for the purpose specified.
10. In a carbureter, the combination of an oil-storage tank or reservoir; an oil-supply tank supported above said storage-tank; a pump for delivering oil to said supply-tank; a carbureter arranged within said oil-storage tank, connected to said oil-supply tank; a service-pipe connected to said carbureter; an air-supply pipe; a valve therefor; an oil-valve; connections for said air and oil valves whereby said oil-valve is controlled by the opening and closing of said air-valve; and pressure-regulators for said air-supply and service pipes, all coacting for the purpose specified.
11. In a carbureter, the combination of an oil-storage tank or reservoir; an oil-supply tank supported above said storage-tank; a pump for delivering oil to said supply-tank; a carbureter arranged within said oil-storage tank, connected to said oil-supply tank; consisting of a main carbureter-chamber and an auxiliary carbureter-chamber, connected by a vertical pipe or tube; perforated baffle-plates arranged in said chambers, the perforations of the adjacent baffle-plates being zigzagged; screens *c* forming partitions in said connecting-tube for said carbureter-

chambers; a packing of absorbent material between said partitions; a service-pipe connected to said main carbureter-chamber toward the bottom thereof; and an air-supply pipe, all coacting for the purpose specified.

12. In a carbureter, the combination of an oil-storage tank or reservoir; an oil-supply tank supported above said storage-tank; a pump for delivering oil to said supply-tank; a carbureter arranged within said oil-storage tank, connected to said oil-supply tank; a

service-pipe connected to said carbureter; and an air-supply pipe, all coacting for the purpose specified.

In witness whereof I have hereunto set my hand and seal in the presence of two witnesses.
